HIRAM INGRAHAM, OF ARMADA, MICHIGAN.

Letters Patent No. 100,768, dated March 15, 1870.

IMPROVEMENT IN HORSESHOES.

The Schedule referred to in these Letters Patent and making part of the same.

To all whom it may concern:

Be it known that I, HIRAM INGRAHAM, of Armada, county of Macomb, and State of Michigan, have invented a new and useful Improvement in Horseshoes; and I do declare that the following is a true and accurate description thereof, reference being had to the accompanying drawings and to the letters of reference marked thereon and being a part of this specification.

Figure 1 is a perspective view of my invention.

Figure 2 is a section of the same, showing the shape of the iron used in its construction.

The object of this invention is to construct a horseshoe, which, while equally as lasting as those constructed in the ordinary way, will, by the form in which it is made, effectually prevent clay or snow from clogging the foot.

In order to accomplish this end I make the slice of what is termed "half-round" iron, of any suitable size, bent into the proper form, turning up the ends

to form the heel-calks A, when the toe-calks B may be secured and attached in the usual way.

A channel, C, should be made outside the "curve" of the convexity of the shoe, to receive the nail-heads with which the shoe is secured to the foot. This channel may be cut inside the curve of the convexity, but I deem the outside the better position for it.

By constructing the shoe in the manner above described, I save more than half the labor usually expended upon a horseshoe, besides entirely preventing the accumulation of mud or snow in the foot.

What I claim as my invention, and desire to secure by Letters Patent, is—

As a new article of manufacture, a horseshoe constructed of half-round iron, as and for the purposes set forth.

HIRAM INGRAHAM.
